UNITED STATES PATENT OFFICE.

GUY W. THAXTON, OF FAIRFIELD, ALABAMA.

SIGNALING SYSTEM.

1,353,436.

Specification of Letters Patent. Patented Sept. 21, 1920.

Application filed April 22, 1919. Serial No. 291,914.

To all whom it may concern:

Be it known that I, GUY W. THAXTON, a citizen of the United States, residing at Fairfield, in the county of Jefferson and State of Alabama, have invented certain new and useful Improvements in Signaling Systems; and I do hereby declare the following to be a full, clear, and exact description of the invention, such as will enable others skilled in the art to which it pertains to make and use the same.

This invention relates to signaling systems, and more particularly to signaling systems of the railway block type.

One of the main objects of the invention is to provide a signaling system of the character stated specially adapted for use in connection with electric railways in which, when a train is one block, the available current in the preceding block will be materially decreased so as to reduce the speed of an approaching train and give warning of the presence of the train in the block ahead.

A further object is to provide a system of this character of simple construction and operation which may be readily installed at comparatively small cost and without necessitating expensive changes in the construction of the railway.

Further objects will appear from the detailed description.

In the drawings:

Figure 1 is a diagrammatic view of a system constructed in accordance with my invention as applied.

Fig. 2 is a similar view of a modified form.

The railway track designated generally by A is divided into a plurality of blocks by means of insulating members 1, three of these blocks designated respectively a, b, and c being shown. A suitable conductor 2, such as a trolley wire or a third rail, is disposed parallel with the track and is divided by insulating members 1' into blocks a', b', and c' which correspond in length to the blocks of the track. An electric generator 3 of suitable type is connected by a wire 4 to block c of the track, through suitable impedance coils 5. The coils 5 are connected by a wire 6 to similar coils 7 which are connected to the tracks of block b at one end thereof, impedance coils 8 being connected to the rails of block b adjacent the other end thereof, these coils 8 being connected by a wire 9 to similar coils 10 which are connected to the

rails of block a. In this manner, the various blocks of the track are connected to one side of the generator so as to receive current therefrom. The other side of generator 3 is connected by a wire 11 to a feed wire 12 which is continuous and is disposed parallel with the trolley wire 2. Feed wire 12 is connected to each of the blocks of the trolley wire by a lead 13 in which is interposed a relatively high resistance 14, this lead being also provided in advance of the resistance with two spaced switch jaws 15 which are adapted to receive the blades of a switch arm 16 which is normally held in operative position by a tension spring 17 having one end secured to the stem 18 of the blade, the other end of this spring being secured to a fixed member. Switch blade 16 carries an armature 19 disposed oppositely to stem 18, this armature being slideable in a solenoid 20. By energizing this solenoid, the switch arm 16 is moved into inoperative position so as to cut the resistance 14 into the circuit of the trolley block b' thus materially reducing the available current in this block.

An alternating current generator 21 of suitable type is connected by leads 22 and 23 to two mains 24 and 25, respectively, which are disposed parallel with the track. Main 24 is connected by a lead 26 with one end of a primary coil 27 the other end of which is connected by a lead 28 with main 25. This primary coil is positioned closely adjacent a secondary coil 29 the ends of which are connected by leads 30 and 31 to the respective rails of block b. Primary coil 27 induces a current in the secondary coil 29, this current flowing through the leads 30 and 31 to the tracks of block b.

An electro-magnet 32 is positioned adjacent the other end of block b and has the opposite ends of its coils connected to the respective tracks of this block by leads 33 and 34 respectively. The secondary current induced in the secondary coil 29 normally flows, by means of leads 30 and 31 and the tracks of block b, and leads 33 and 34 through the coil of electro-magnet 32 so as to energize the same. This magnet serves to normally hold a pivoted armature 35 in raised position in engagement with its upper contact 36. This armature is connected at its pivot by a wire 37 with one side of an electric battery 38 the other side of which is connected by a wire 39 with one

side of an electrically operated signaling device 40 which includes a movable signaling arm 41, the other side of which is connected by a wire 42 with contact 36. When 5 armature 35 is in raised position, the circuit for the electrically operated signaling device 40 is completed and the arm 41 is held in position to indicate that the block is clear or open. Block *c* is provided with a similar electro-magnet 32' the opposite sides of which are connected by leads to the respective rails of the block, this magnet serving when energized to hold in raised position a pivoted armature 35', this armature engaging 10 a contact 36' for closing the circuit of an electric battery 38' so as to energize the electrically operated signaling device 40'. It will be understood, of course, that block *c* is provided adjacent its other end with a secondary coil corresponding to coil 29 and having its ends connected to the respective rails of the block, a primary coil being positioned adjacent the secondary coil and having its opposite ends connected to mains 24 and 25, the electro-magnet 32' being energized by the secondary or induced current. The lower contact 43' for armature 35' is connected by a wire 44' to one side of the coil of solenoid 20, the other end of the solenoid being connected by a wire 45' to the main battery wire 46' at the opposite side of the battery from wire 47' for connecting the armature, at its pivoted end, to the battery. As will be readily understood, the 30 lower contact 43 for armature 35 is connected by a wire 44 to one side of a solenoid corresponding to solenoid 20, the other side of which is connected by a wire 45 to battery wire 39. It will be understood that the 35 solenoid to which the wires 24 and 25 are connected serve to operate a control switch for cutting a resistance corresponding to resistance 14 into the trolley circuit of block *a* at proper times.

40 By arranging the various circuit control means in the manner described, I insure that when a train is in one block, the current available in the block behind will be materially reduced so as to reduce the speed of an approaching train while also warning the engineer of this approaching train of the presence of a train in the block toward which it is traveling. This will be better understood by reference to the diagram in 45 which the truck of a car is indicated diagrammatically as entering block *c*, this truck being indicated by 47. The truck 47 carries a motor 48 of suitable type, one side of which is connected by a lead 49 to a trolley pole 50 which carries at the upper end the trolley engaging member or wheel 51, the other side of the motor being grounded through the wheels of the truck to the rails of the track. When the truck 60 55 enters block *c*, electro-magnet 32' is short

circuited thus permitting the armature 35' to drop into engagement with contact 43'. This breaks the circuit of signaling device 40' so as to move signaling arm 41' thereof into position to indicate that block *c* is occupied or closed. The armature 35' when lowered closes the circuit for solenoid 20, current flowing from the positive side of battery 38' through wire 46', wire 45', the solenoid, wire 44', contact 43', armature 35', and wire 47' back to the negative side of the battery. This energizes the solenoid so as to move the switch arm 16 into open or inoperative position thus cutting the resistance 14 of section or block *b*' of the trolley wire 2 into the trolley circuit of this block. This materially reduces the available current in block *b* so that a train entering this block would have its speed materially reduced thus warning the engineer of the 85 train of the fact that block *c* is occupied while also materially reducing the speed of the train entering block *b* so as to eliminate all possibility of accident. The train in block *b* may then travel at very slow speed 90 and is at all times under control so as to effectually prevent a collision between this train and the train in block *c*. In the same manner, when a train enters block *b* the resistance will be cut into the trolley circuit 95 of block *a* so that, when a train is in any block of the system, another train entering the preceding block will have its speed materially reduced and will be thus warned of the train ahead. This insures ample 100 warning and effectually eliminates all danger of accident, since this warning is in no way dependent upon the engineer of the train or any other individual, the operation of the signaling system being automatic. 105

In the modified form illustrated in Fig. 2, wire 45' is broken to provide two wires 45' and 45''. Wire 45' is connected by a wire 55 to wire 37, and wire 45'' is connected by a wire 56 to wire 44. With these connections, when truck 47 enters block *c*, armature 35' will drop, but the circuit of solenoid 20 will not be completed due to the fact that armature 35 is held in raised position by electro-magnet 32. However, if a train enters block *b* while there is a train in block *c*, electro-magnet 32 will be short circuited so as to cause armature 35 thereof to drop thus completing the circuit of solenoid 20 about the battery 38 through wires 45'', 56, truck 115 47, contact 43, armature 35, wire 37, and wires 55 and 45'. This serves to cut the resistance 14 into the trolley circuit of block *b* thus materially reducing the speed of the train entering this block in the manner and 120 for the purpose previously described. In all other respects, the operation of this modified form of the signaling system is identical with that illustrated in Fig. 1.

While I have described my system as used 130

in connection with a direct current generator for generating the traction power, it may be equally well used in connection with an alternating current generator. Also, 5 when a train enters a block the available current in the block behind is materially reduced, as stated, regardless of the direction of travel of the train. By this means, if a train is in one block and a second train backs into the block ahead, the first train 10 will be notified and will have its speed materially reduced. Also, if the second train attempts to back into the block occupied by the first train, it will have its speed suddenly materially reduced when passing from 15 one block to the other. This serves to warn both trains and to also reduce their speed of travel, thus effectually preventing rear end collisions.

20 What I claim is:

1. In a signaling system for electric railways, a railway track divided into a plurality of blocks electrically insulated from each other, a trolley wire divided into blocks 25 corresponding to the blocks of said track, means for supplying electrical energy to the respective blocks of said trolley wire and to the rails of said track, and means controlled by a train traveling upon said track 30 for reducing the available electrical energy in the trolley circuit of the block behind that occupied by the train so as to reduce the speed of a second train entering said block behind.

35 2. In a signaling system for electric railways, a railway track divided into a plurality of blocks electrically insulated from each other, a trolley wire divided into blocks corresponding to the blocks of the track, means 40 for supplying current to the track and to the respective blocks of said trolley wire, and means controlled by a train traveling upon said track for introducing a relatively

high resistance into the trolley circuit of the block behind the block occupied by said 45 train so as to materially reduce the current available in the block behind for reducing the speed of travel of a second train entering said block.

3. In a signaling system for electric rail- 50 ways, a track divided into a plurality of blocks electrically insulated from each other, a trolley wire divided into blocks corre- 55 sponding to the blocks of said track, a con- tinuous feed wire, means for supplying cur- 60 rent to said wire and to the tracks, connec- tions between the feed wire and the respec- 65 tive blocks of the trolley wire including switch jaws electrically connected to the feed wire and the trolley wire respectively, 70 and a resistance connected at its opposite ends to said jaws, switch arms provided with contact blades engageable into said jaws, 75 said arms being normally held in operative position so as to establish direct electrical 80 connection between the feed wire and the blocks of the trolley wire, solenoids having slideable armatures connected to the respec- tive switch arms for moving the same into inoperative position when the solenoids are energized, electromagnetic means connect- 85 ed to the tracks of the respective blocks for normally breaking the circuits of the sole- noids of the two adjacent blocks immedi- ately behind, and means for energizing the 90 solenoids of such blocks, respectively, when the circuit of the said electro-magnetic cir- cuit breaking means are short circuited by a train entering said blocks.

In testimony whereof I affix my signature 80 in presence of two witnesses.

GUY W. THAXTON.
